J. A. HOGE.

BELLOWS OPERATING MECHANISM FOR PLAYER PIANOS.

APPLICATION FILED FEB. 1, 1917.

1,295,989.

Patented Mar. 4, 1919.

UNITED STATES PATENT OFFICE.

JOHN A. HOGE, OF NEW YORK, N. Y.

BELLOWS-OPERATING MECHANISM FOR PLAYER-PIANOS.

1,295,989.

Specification of Letters Patent.

Patented Mar. 4, 1919.

Application filed February 1, 1917. Serial No. 145,974.

To all whom it may concern:

Be it known that I, JOHN A. HOGE, a citizen of the United States, residing at New York city, in the county of New York and State of New York, have invented certain new and useful Improvements in Bellows-Operating Mechanism for Player-Pianos, of which the following is a specification.

This invention relates to player pianos, and more particularly to motor driven bellows operating means therefor.

The main object of the invention is to provide means of this character so constructed as to dispense entirely with the use of pedals for operating a player piano.

Another object is to provide bellows operating means for a player piano which may be applied to any instrument of this character already in use without necessitating any change in the piano construction other than to omit the pedals, and this omission is not necessary, but is optional with the owner.

Another object is to provide operating means of this character which may be applied to pianos in which the bellows are arranged close together as well as to those in which they are spaced wide apart.

Another object is to provide operating means for connecting the device to the movable member of the bellows whereby the bellows is operated when the motor is actuated.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:

Figure 1 represents an end elevation of one form of bellows operating mechanism constructed in accordance with this invention, a fragment only of a piano being illustrated and the base plate thereof being shown in section.

Fig. 2 is a plan view thereof.

Fig. 3 is a front view of a fragment of a

piano showing another form of this invention applied.

Fig. 4 is a plan view thereof.

In the embodiment illustrated, a fragment of a player piano is shown, 1 designating the base plate and 2 and 3 the bellows which are of the construction usual in instruments of this character.

In Figs. 1 and 2, the bellows operating means constituting this invention is shown applied to a piano in which the bellows 2 and 3 are arranged somewhat close together, while in Figs. 3 and 4, the mechanism in a slightly different form is shown applied to a piano in which the bellows are disposed farther apart.

In the form shown in Figs. 1 and 2, a double-armed crank shaft 4 is journaled intermediate its ends in a standard 5 and at its ends in bearings 6 and 8, fixed to the outer face of the stationary members B and B' of the two bellows. Another bearing 7 is also carried by the bellows member B' in transverse alinement with the bearing 8, the outer end of the shaft 4 extending entirely across this bellows member and hence the necessity for employing two bearings. The bearings 6, 7 and 8 are each provided at their outer ends with extensions 9 which project beyond the edges of the bellows members B and B' so as to space the intermediate crank arms 10 of the shaft 4 and a pulley 11 carried by one end of said shaft away from the bellows members to prevent engagement of the latter by said elements and the wear consequent to said engagement.

The pulley 11 is connected by a belt 12 with a motor driven pulley 13 whereby the shaft 4 is operated.

The motor indicated at M may be housed in a sound-proof box and it may be controlled by a push-button (not shown) placed at a convenient point.

Combined attaching and reinforcing plates 14 and 15 are secured to the opposed inner edges of the movable members b and b' of the bellows as is shown clearly in Fig. 2. These plates are L-shaped in cross section, the short arms as 16 thereof being engaged with the edges of the members b and b' and 100

secured thereto by any suitable fastening means. The longer arms 17 overlap the outer faces of the bellows members and reinforce them at this point, although these 5 reinforcing portions may be omitted if not deemed necessary.

Pitmen 18 are connected at one end with the crank portions of the arms 10 of shaft 4 and at their other ends are pivotally connected with the plates 14 and 15 by studs 19 carried by the short arms of the reinforcing and attaching plates 14 and 15, said studs being preferably threaded at their free outer ends with which ends are engaged nuts 20. 10 The ends of the pitmen which are connected with the crank arms of the shaft are held in engagement therewith by suitable bearing plates 21 to provide for the assembling of the parts and the ready detachment of one 15 of the pitmen when it is found necessary or desirable.

From the above description it will be obvious that when the motor is set in operation, the pulley 13 connected therewith will be driven thereby and motion imparted to pulley 11 through belt 12. The driving pulley 11 will cause shaft 4 to be rotated and its connection by pitmen 18 with the movable bellows members *b* and *b'* will cause the operation of the bellows, one of 30 which is operated alternately with the other, as is shown clearly in Fig. 2.

In the form shown in Figs. 3 and 4, the bellows 2' and 3' are placed farther apart 35 than those shown in the other figures above described and the operating shaft 4' with the driving pulley 11' thereon are arranged between said bellows. In this form of the invention the shaft 4' is rectilinear throughout its length and is shown journaled in a bifurcated standard 5', the upper ends of the furcations of which have removable bearing members 21' to provide for the assembling of the parts. The driving pulley 45 11' is shown fixed to the shaft 4' midway its ends and operates between the furcations of the standard 5'. A belt 12' connects pulley 11' with a motor driven pulley 13', all of which parts are similar to those above 50 described, the only difference being in the location of the pulley 11', which instead of being at the outer end of the shaft is disposed midway its ends. Two crank disks 22 and 23 are fixed to the opposite ends of shaft 4' and have crank pins 24 projecting laterally from their outer faces. Pitmen 55 18' connect the crank pins 24 with pins 19' which project laterally from the attaching and reinforcing plates 14 and 15' carried 60 by the movable bellows members *b* and *b'* in a manner similar to that above described. The pitmen 18' are secured to the pins 24 at a point sufficiently remote from the disks 22 and 23 to permit the turning of the disks 65 without the engagement of the heads of

pins 19' with the disks. The crank pins 24 are preferably threaded and provided at their outer ends with securing nuts 24'.

In the use of this form of the invention the pulley 11' being driven by the motor 70 driven pulley 13' imparts its motion to the crank shaft 4' which through the crank disks 22 and 23 and pitmen 18' connected therewith and with the bellows members *b* and *b'* operate to actuate the bellows alternately in relation to each other in the same manner as that described above in connection with the other form of the invention. 75

From the above description it will be obvious that this mechanism may be applied to a piano already constructed without any change in the parts thereof, the supports for the crank shafts being carried by the standards mounted on the base plates of the 80 piano and by the stationary bellows members without marring or mutilating either of them. It will also be obvious that this mechanism may, with slight modification in the manner of attaching, be applied to various styles of player pianos and that it may be operated interchangeably with the pedals so that the piano may be played either automatically by a motor or by foot power as 85 may be found desirable. 90

The crank disk form of propeller shown in Figs. 3 and 4 is designed primarily for standard action pianos in which the bellows are set far apart allowing sufficient space for the placing of both the motor and the 100 propeller centrally between said bellows whereby the power for rotating the shaft is imparted thereto midway its ends. 95

The double-armed crank shaft style of propeller shown in Figs. 1 and 2 is designed 105 to apply to other makes of player pianos in which the bellows are arranged close together.

From the foregoing description, taken in connection with the accompanying drawing, 110 the advantages of the construction and of the method of operation will be readily apparent to those skilled in the art to which the invention appertains and while I have described the principle of operation of the 115 invention together with the device which I now consider to be the best embodiment thereof, I desire to have it understood that the device shown is merely illustrative and that such changes may be made as are within 120 the scope of the claimed invention. 120

I claim:

In combination, a pair of bellows, each including a vertically disposed fixed leaf and a movable leaf hinged to each fixed 125 leaf, the fixed leaves lying in the same plane, a bearing disposed between the fixed leaves, a pair of bearings mounted on the face of one fixed leaf, a crank shaft having a pair of oppositely extending offset portions, one 130

relatively long end journal, a relatively short end journal and an intermediate journal, the long journal being located in the pair of bearings of the said fixed leaf, a bearing on

- 5 the other fixed leaf to receive the short journal, pitmen connected to said offsets and to their respective movable leaves, and a

pulley mounted on the long journal of the shaft.

In testimony whereof I affix my signature 10 in presence of two witnesses.

JOHN A. HOGE.

F. SEYMOUR STURDEVANT,
A. EDWARD BASCOM.
